UNITED STATES PATENT OFFICE.

LUTHER D. LOVEKIN, OF PHILADELPHIA, PENNSYLVANIA, ASSIGNOR TO WESTINGHOUSE ELECTRIC & MANUFACTURING COMPANY, A CORPORATION OF PENNSYLVANIA.

APPARATUS FOR CONSERVING HEAT.

1,232,593.

Specification of Letters Patent.

Patented Jan. 8, 1918.

Application filed June 15, 1915, Serial No. 34,206. Renewed November 26, 1917. Serial No. 204,099.

To all whom it may concern:

Be it known that I, LUTHER D. LOVEKIN, a citizen of the United States, and a resident of Overbrook, Philadelphia, in the county of Philadelphia and State of Pennsylvania, have made a new and useful Invention in Apparatus for Conserving Heat, of which the following is a specification.

This invention relates broadly to conservation of heat and has for an object to provide means for conserving the heat withdrawn from a condenser by the removal of the water of condensation and the air or non-condensable vapors from the condenser.

10 A further object is to produce an organized apparatus for conserving the heat contained in the water of condensation and the air and non-condensable gases withdrawn from a condenser, for conserving the heat 15 contained in the steam exhausted from the 20 ejecting apparatus employed for withdrawing the air and non-condensable gases and for separating the air and non-condensable 25 gases from the water contained within the apparatus.

A further object is to produce a feed water heater to which the water of condensation and the air or non-condensable gases withdrawn from a condenser are delivered, 30 and in which means are employed for separating the air and non-condensable gases from the water within the heater.

35 A further object is to produce a feed water heater adapted to receive the water of condensation withdrawn from a condenser and the steam exhausted from an ejector or other apparatus employed for evacuating the condenser, in which means are employed for eliminating the noise ordinarily occasioned by mixing steam and water.

These and other objects are attained by means of apparatus embodying the features herein described and illustrated in the drawings accompanying and forming a part 45 hereof.

In the drawings I have diagrammatically illustrated apparatus embodying my invention, with a portion of the apparatus shown in section for convenience of illustration.

50 The illustrated embodiment of my invention includes a condenser 3 of any type, an ejecting device 4 for withdrawing the air and non-condensable gases from the condenser, apparatus such as a pump 5 for

50 withdrawing the water of condensation from the condenser, and a combined feed water heater and air separator 7 to which the water of condensation and the air or non-condensable gases withdrawn from the condenser are delivered.

60 As illustrated, the heater consists of a receptacle provided with a port 8 through which water of condensation and the air or non-condensable gases withdrawn from the condenser are delivered. The receptacle is also provided with an air vent port 9, a water delivery port 10 and a port 11 through which an auxiliary supply of water may be delivered to the heater. The port 9 is preferably located in the top of the heater 65 casing and the port 8 is located above the normal water level of the heater and preferably in one side of the heater casing. In the drawings I have shown a tray or trough 12 located within the casing for receiving 70 the water delivered to the heater through the port 11 and for delivering the water in drops, thin streams or sheets to the bottom 75 of the heater. The bottom of the tray is therefore provided with a series of water 80 delivery apertures 13, which are arranged to deliver the water in drops, thin sheets or streams through the path of fluid entering the heater through the port 8. The tray may also be provided with air vent apertures 85 14 for delivering to the port 9 the air which may be entrained with the water entering the port 11.

85 As illustrated, the air or non-condensable gases are withdrawn from the condenser by 90 means of a steam actuated ejector 4, the inlet of which communicates with the air offtake of the condenser through a piping or passage 15, and the discharge of which communicates with the port 8 of the heater through a pipe 95 17 and a diffuser 16. The condensate discharge pump 5 communicates with the condensate discharge port of the condenser and is adapted to deliver the water of condensation withdrawn from the 100 condenser to the discharge piping of the ejector 4. As illustrated, the delivery piping 17 of the pump communicates with the annular delivery nozzle 18, located within the discharge piping of the ejector, and arranged to deliver the water, received by it, to the inlet end of the diffuser 16. The water delivery nozzle is preferably so arranged 105

that the water issuing from it is delivered around a discharge nozzle 19, which communicates with the exhaust of the ejector 4, and through which air or non-condensable 5 gases and steam discharged from the ejector are delivered. With this arrangement the water of condensation and the steam and air withdrawn from the condenser are intimately mixed prior to or at the time of being delivered to the heater. In addition to this, the steam issuing from the ejector is condensed by being brought into contact with the cooler water issuing from the nozzle 18 and consequently it imparts heat to the 10 water. The intermingling of the air and water also causes the water to take up heat from the air and the air after being liberated in the heater 7 is discharged therefrom through the vent port 9.

20 One of the advantages of the invention is that substantially all the heat withdrawn from the condenser is conserved and is delivered to the feed water heater. In addition to this, the method employed for mixing the water with the heating steam largely eliminates the noise which is usually encountered in feed water heaters. Another feature of the invention is that the nozzle 19 may be so constructed that the fluid issuing therefrom into the diffuser 16 will exert an injector action on the water delivered by the pump 5 and in this way aid the pump by reducing the back pressure on it.

In accordance with the United States patent statutes I have illustrated and described one embodiment of my invention, but I desire it to be understood that various changes, modifications, substitutions, additions and omissions may be made in apparatus illustrated without departing from the spirit and scope of the invention as set forth by the appended claims.

What I claim is:

1. In combination with a condenser, a fluid actuated ejector for withdrawing non-condensable gases from the condenser, a feed water heater having an air vent port and an inlet port through which said ejector discharges into the heater, and a single pump 45 for withdrawing water of condensation from the condenser and for delivering it with the fluid discharged from the ejector through the inlet port to said feed water heater.

2. Apparatus for conserving heat, comprising a feed water heater having an air

60 vent port, a condenser, a steam actuated ejector for withdrawing the noncondensable fluids from the condenser, means for delivering the fluids exhausted from the ejector to the heater, a pump for withdrawing the water of condensation from the condenser and means for mixing the water of condensation with the fluid exhausted from the 65 ejector before it reaches the heater and for delivering the mixture to the heater. 65

3. Apparatus for conserving heat, comprising a condenser, a feed water heater having an air vent port formed therein, a fluid actuated ejector for withdrawing noncondensable gases from the condenser, piping 70 between the exhaust of the ejector and an inlet port with which said heater is provided, means for withdrawing the water of condensation from the condenser, and a liquid delivery nozzle located within said piping and 75 to which water withdrawn from the condenser is delivered.

4. Apparatus for conserving heat, comprising a condenser, a fluid actuated ejector for withdrawing noncondensable gases from 80 the condenser, a feed water heater having an air vent port, a diffuser communicating with an inlet port of said heater and with the exhaust of the ejector, a water delivery nozzle for delivering water through the diffuser to 85 the heater, and means for withdrawing water of condensation from the condenser and for delivering it to said nozzle.

5. Apparatus for conserving heat, comprising a condenser, a fluid actuated ejector for withdrawing noncondensable gases from 90 the condenser, a feed water heater having an air vent port, a diffuser communicating with an inlet port of said heater, a fluid delivery nozzle communicating with the exhaust of 95 the ejector and projecting into the diffuser, a condensate pump for withdrawing water of condensation from the condenser, and an annular nozzle surrounding said fluid delivery nozzle for delivering water discharged from 100 said pump through said diffuser to said heater.

In testimony whereof, I have hereunto subscribed my name this twelfth day of June, 1915.

LUTHER D. LOVEKIN.
